UNITED STATES PATENT OFFICE.

ALEX FISCHER, OF KENSINGTON, LONDON, ENGLAND.

TALKING-MACHINE.

1,184,938.

Specification of Letters Patent. Patented May 30, 1916.

Application filed December 4, 1911. Serial No. 662,880.

To all whom it may concern:

Be it known that I, ALEX FISCHER, a subject of the King of England, residing at 8 Maclise road, Kensington, London, England, have invented certain new and useful 5 Improvements in and Relating to Talking-Machines, of which the following is a specification.

This invention relates to talking machines, 10 and refers more particularly to improvements in talking machines of the cabinet type in which the top or cover or the doors of the cabinet, coming at the mouth of the trumpet are used as reflecting or directing 15 surfaces for the sound.

With machines of the cabinet type it has 20 already been proposed to provide a hinged cover coming above the mouth of a vertical trumpet or hinged doors at the side of the cabinet and at the mouth of the trumpet, 25 which cover or doors may be used for reflecting the sound. The cover or each door, has, however, been made in one piece so that it has been possible to reflect the sound waves in one direction only, for one position 30 of the door or cover.

My present invention refers to a construction, 35 in which the top or door of the cabinet, while being so formed as to be capable of being turned into various positions, is itself furnished with one or more secondary hinged or sliding flaps or strips, forming a reflecting surface or surfaces which can be brought into a large number of different 40 positions and retained in such positions independently of one another when desired, in order that the sound may be reflected either in one direction only, as has already been the case or in various directions at the same 45 time and in various ways to suit requirements.

Where a cabinet is not used, I provide a reflecting device adapted to be mounted at the mouth of the trumpet of a talking machine, 50 which reflecting device is provided with a secondary hinged or sliding flap or flaps or strips before mentioned.

In one way of carrying out my invention I provide a cabinet which is preferably 55 square in plan. Toward one corner on the bottom board I mount a turntable, the motor being suitably located for this purpose beneath the bottom board. Toward the diagonally opposite corner I mount the bracket for holding the tone arm. Leading from the tone arm is a bent tube, which is so

bent that it leads to an orifice coming at the center of the cabinet where it opens into a vertically disposed trumpet, which may be suitably attached to the casing of the cabinet. The trumpet extends to the top of the cabinet, coming beneath the lid or cover. This lid or cover is hinged so that it can be turned up to and fixed at any angle desired above the trumpet, suitable means being provided for keeping it in position.

The cover is made in two or more pieces which are hinged with respect to each other or which slide with respect thereto in such a way that they may be brought into and retained in position so that the whole constitutes one or more reflecting surfaces, and the reflecting surfaces may be simple reflecting surfaces or form resonating chambers of any desired type with holes in the sides.

In order that this invention may be better understood, I will now proceed to describe the same with reference to the drawing accompanying this specification in which:—

Figure 1 is a front elevation of the machine with the doors open; Fig. 2 is a sectional plan; Fig. 3 is an enlarged view of the top of the cabinet; Fig. 4 is a plan view of same. Fig. 5 is a similar view to Fig. 4 of a slightly modified form. Fig. 6 is a sectional view on the line A—B of Fig. 5 looking in the direction of the arrow. Figs. 7 to 12 are partly diagrammatic views of the cabinet showing different kinds of covers, and also showing the cover in some of the different positions it can be made to assume. Fig. 13 illustrates how a reflector with adjustable flaps may be applied adjustably directly to the mouth of the horn. Fig. 14 shows another form of the reflector applied adjustably to the top of a cabinet. Fig. 15 is a plan view of still another form of reflector with sliding flaps. Fig. 16 is a plan view of a portion of a reflector provided with a resonating chamber. Fig. 16^a shows a transverse section thereof. Fig. 17 is a perspective view showing still another way of applying reflectors to the top of a cabinet in such manner that they may be adjusted relatively to the mouth of the horn and relatively to each other. Figs. 18 and 19 show other ways of applying reflectors to the mouth of the horn of a talking machine.

The cabinet *a* which is preferably square in plan is provided with a board *b* beneath which is located the motor *c* in such a way

that the turntable *d* comes toward one corner. Toward the diagonally opposite corner is mounted the bracket *e* for holding the tone arm *f*. Leading from the tone arm *f* is a bent tube *g* which is so bent that it leads to an orifice *h* coming at the center of the cabinet *a* where it bends into a vertically disposed trumpet *k*, which may be attached to the cabinet *a*. It will be seen that the trumpet extends to the top of the cabinet *a* coming beneath the lid or cover. This lid or cover is hinged to the cabinet at *m*.

The cover in the particular case under consideration is made as follows:—*n* is a strip 15 extending across the back of the cabinet to which strip is hinged a framework *p* by means of hinges *q*. This framework has hinged thereto two flaps *r* by means of hinges *s*. The frame *p* supports the flaps *r* 20 when in the closed position. *t* are two other flaps which are hinged at *u* to the front portion of the flaps *r*. These flaps can be turned outward upon the hinges *u*. At Figs. 5 and 25 6 a form of the invention is shown in which other flaps *z* are provided hinged at 2 to the side flaps *r*. The hinged flap *z* is only shown attached to one of the flaps *r* but flaps *z* may of course be provided for each of the flaps *r*. The frame *p* is provided with notches 3 at 30 the sides and the flaps are provided with rods 4 the ends of which are adapted to take into one of the notches 3 so that the flap *r* can be held open at the required angle.

Referring to Figs. 7 to 12, which show 35 some of the different positions which the cover can be made to assume, at Fig. 7 the cover is shown turned up about the hinges *m* and held in position by means of a rod 5. At Fig. 8 the strip *n* is turned up into a 40 vertical position about the hinges *m* and then the cover is turned about the hinges *g* and held in position by the rod 5 which is provided with an extensible end for this purpose. In this figure the flaps *t* are shown 45 dotted in the turned up position.

In Fig. 9 the piece *n* is turned up into the vertical position about the hinges *m* and the frame *p* is held in the horizontal position by means of a block or rod 5 and then the 50 flaps *r* are turned up into a raised position and retained therein by means of the rod 4 engaging in the notches 3. In this figure one of the side flaps is shown with the extension piece *z* dotted in position. At Fig. 10 55 is an arrangement similar to that described with reference to Fig. 9, but in this case only one of the flaps is turned upward the other one being left upon the frame *p*. At Fig. 11, the cover is turned about the hinges *m* 60 and held in position by the rod 5 and then one of the flaps *r* is turned up and held in position by the rod 4 resting in one of the notches 3. At Fig. 12 the strip *n* is turned 65 into the vertical position about the hinges *m* and the frame *p* is then turned about the hinges

q and secured in the upper position by the extended rod 5, and then both of the flaps *r* are turned into the upward position and retained in position by means of the rods 4 resting in the catches 3. In this figure one 70 of the extensions *z* is shown.

It will be understood that the methods of arranging the cover described with reference to Figs. 7 to 12 are merely representative as with the same construction of cover other 75 combinations may be made, for instance, both the flaps *r* may be turned up and both the flaps *t* turned out as also both the flaps *z* and many other combinations may be made to suit requirements.

Although I have described and shown the second flaps as hinged with respect to the principal flaps I may in some cases make them slide with respect thereto either at the front or the sides. This feature of the invention is shown in Fig. 15 in which A, A, 80 indicate the main reflecting sections which are hinged together at A' so that they may be opened to any desired extent and placed at any desired angle relatively to each other 85 or to the mouth of the horn. Each section carries a sliding section or flap B and another sliding flap C. The reflector shown in Fig. 15 as a whole can be suitably mounted over a horn in the manner before described 90 and great variety in intensity, volume and quality of sound, as well as in the direction of movement of the sound waves, can be obtained. The flaps may be made of any suitable material and they may be made so as 95 to be detachable and interchangeable.

Although I have described two flaps hinged to the cover I may provide more than two hinged or sliding flaps and I may arrange them to turn up or draw out in any 100 suitable direction. I may also hinge the two flaps forming the reflecting surfaces in such a way that the hinge lies in a diagonal across the top of the cabinet or in any other desired direction. This is illustrated in Fig. 110 17 where the reflectors D, D are hinged to the top of the cabinet at *d* in a line extending diagonally across the cabinet and the reflectors may be held at any desired angle 115 relatively to the mouth of the horn and at any desired angle relatively to each other by means of the adjustable rods *e*.

Again although my invention relates more especially to machines of the cabinet type I may apply it to trumpets or cheap machines. 120 In this case the trumpet is directed vertically upward and at or over the top thereof I preferably provide a rod or its equivalent which may be hinged and which may extend diametrically across the top of the trumpet 125 and I hinge a flap or flaps thereto which flap or flaps can be turned up into and retained in a suitable position for acting as reflecting surfaces. Other secondary hinged or sliding flaps may be added in connection 130

with the principal flaps. This feature of the invention is shown in Figs. 18 and 19. In Fig. 18 reflectors F are hinged to the horn at *f* and are supported by adjustable rods G also connected with the horn. In Fig. 19 the reflectors H are hinged to each other at *h* and they are hinged to the horn at *i*. The reflectors may be held in any desired position on the horn and given any desired angle by means of the adjusting devices J. In Fig. 19 the reflectors H are provided with adjustable flaps K which are shown extended by dotted lines. One or more of each set of reflectors may be formed with resonating chambers, that is, either or all of the sections may be made hollow as indicated at M in Figs. 16 and 16^a. In Fig. 13 the primary reflector is made in two parts R which may be hinged together, and secondary reflectors or flaps R' are hinged to the top and side edges thereof. In Fig. 14 the primary reflectors S, S' are hinged together at *s* and have hinged to their top edges flaps *s'*, *s*² and to their side edges flaps *s*³, *s*⁴. The flaps *s'*, *s*² also have flaps *s*⁵, *s*⁶ hinged to them. I have shown hinges in a conventional way. It will be understood that hinges of proper form to permit of the folding of the flaps and sections are to be employed, and that suitable adjustable supports wherever necessary are used.

In the claims where I specify a flap it will be understood of course that I also contemplate employing a plurality of flaps.

What I claim as my invention and desire

to secure by Letters Patent of the United States of America is:—

1. The combination with the trumpet of a talking machine, of a primary sound deflector mounted beyond the outer end of the trumpet for receiving the sound waves emanating therefrom and reflecting them outward, said reflector being adjustable to vary the angle of reflection and carrying a sound reflecting flap adjustably mounted whereby it may be supported in various positions to vary the extent of the reflecting surface, and means for supporting the primary reflector at various angles relatively to the axis of the trumpet.

2. The combination with the trumpet of a talking machine, of a primary sound reflector mounted beyond the outer end of the trumpet for receiving the sound waves emanating therefrom and reflecting them outward, comprising a plurality of sections connected together and hinged to a support which sections are adjustably mounted whereby they may be supported in various positions on the primary reflector to vary the marginal extent of the reflecting surface, and means for adjustably supporting the several connected sections at various angles relatively to the axis of the trumpet.

In testimony whereof I have hereunto set my hand in the presence of two witnesses.

ALEX FISCHER.
